EAR PROTECTOR

Thomas Gibbons, Chicago, Ill.

Application March 14, 1952, Serial No. 276,542

4 Claims. (Cl. 128—152)

1

My invention relates to ear protectors which can be worn in the ear without discomfort, and which will protect the ears or ear against damage to the tympanum or drum or ear drum thereof.

An important object of my invention is to provide ear plugs, which may be removably inserted and worn in the ear canal, and which are provided with a frusto-conical insert or plug section to fit frictionally in the ear canal.

Another object of my invention is to provide an article of the aforementioned character, which is provided on its conical surface with a series of circumferential serrations, so as to afford relieved contact with the interior surface of the ear canal, in order to allow sound to partially enter and permit individuals wearing the ear drum protectors to carry on a conversation, in other words, not to totally deafen the wearer.

Another object of my invention is to provide a core opening longitudinally and axially within the body of the said ear drum protector, which will permit the insertion of the ear drum protector without unduly compressing the air within the confines of the ear canal, so as not to subject the tympanum or ear drum to tension or strain.

A further object of my invention is to provide core means which will afford a reduced section to permit the same to be subjected to a partial vibration, the said partial vibration being in turn imparted to the ear drum, so that conversation may be carried on by people wearing the said ear drum protector, without impairing the hearing to a great extent.

A still further object of my invention is to provide an article of the aforementioned character, in which a portion thereof, is subjected to vibration by sound and tonal effects which will create sympathetic vibration on the ear drum or tympanum of the ear, so that slight sounds are transmitted to the ear drum, but will prevent loud noises from rupturing the tympanum or the ear drum, thus protecting the ear drum against noises of tremendous vibration. Thus the air within the ear canal will be permitted to function within the core means aforementioned, and hence aid in subduing the intense vibration to which the ear drum might be subjected by loud noises, in turn, preventing the fracture or rupture thereof.

A still further object of my invention is to provide an article of the aforementioned character, made of resilient material, which may be worn comfortably within the ear, which will not impair hearing for conversation purposes, and which will protect the ear drum against rupture by loud noises coming from detonations or bombing effects, and so simple in construction that it may

2

be economically manufactured in quantity production.

Other objects and advantages resident in my invention will be readily discernible from the accompanying drawings, bearing further elucidation in the ensuing description, wherein like symbols are used to designate like parts, and in which:

Fig. 1 is a sectional view of an ear, showing the anatomical construction thereof, and showing my invention inserted therein, partially in section, in order to disclose the detailed structure thereof.

Fig. 2 is an enlarged view of my invention with a portion thereof broken away in section, in order to clearly illustrate the details thereof.

Fig. 3 is a top view of Fig. 2.

Fig. 4 is a transverse cross-sectional view, taken substantially, on the line 4—4 of Fig. 2.

Fig. 5 is a transverse cross-sectional view, taken substantially, on the line 5—5 of Fig. 2.

Referring to the various views, the ear structure 13, is illustrated in Fig. 1, showing the auditory canal 14 thereof, and the drum or tympanum 15.

25 My invention is generally designated 7 and is shown inserted removably and in frictional engagement within the canal 14 in Fig. 1.

The detailed structure of my invention generally designated 7, consists of the frusto-conical body 8, having a reduced neck 9, and a manipulating handle 10, slightly larger in diameter.

The frusto-conical body 8 is provided with a series of threadlike circumferential ridges 11, so as to minimize the frictional contact therebetween and the interior surface of the auditory canal 14 of the ear 13.

At the bottom thereof, a bore 12 is axially located, it being a blind bore so that the remainder portion 19 above the bottom of the bore 17 is closed.

40 The top of exposed portion 18 of the ear protector 7 is exposed outside of the confines of the auditory canal 14, to permit manipulating the handle 10 when placing the instrumentality within the auditory canal 14, or when removing the same from the auditory canal 14.

45 The tapered structure permits insertion of the article into the auditory canal 14 which may vary in size, depending on the person wearing the same, so that the protector 7 may either enter further into the canal 14, or have the greater portion thereof exposed.

50 The contact of the ridges 11 with the interior surface of the auditory canal 14, thus provide open circumferential portions or circular portions, which permit some sound and tone effects or vibrations to pass to the drum 15, at the same time, the portion 19 between the bottom of the bore 17, and the top surface 18, which is more or less solid, is partially subjected to vibration,

which in turn subjects the ear drum 15, to sympathetic vibration, thus only part of the tonal effects are registered on the drum 15, and permit the individual wearing the protector 7 to hear conversations which may be carried on while the article 7 is worn.

At the same time, any disastrous effects to the ear drum 15, are prevented, in view of the fact that the portion 19, which is subjected to outside tone influences, will only partially respond to those influences, and therefore merely cause a partial reaction on the ear drum 15, so that the effects of bombing, detonation and other noises which ordinarily would rupture or fracture an ear drum 15, would not, in this particular instance, cause such damage to the ear drum 15, affording protection thereto, at such times, without impairing the hearing to the extent that individuals wearing the ear protector 7, could not carry on conversation.

The article for its effective use and purpose, is merely inserted frictionally into the auditory canal 14, until a firm engagement thereof is felt by the wearer, without necessarily forcing the same to cause any material discomfort. The article inserted in this manner, because of its conical structure, permits some of the air in the auditory canal 14 to be displaced, and when engaging the same frictionally, so as to say in the auditory canal 14, the added pressure required for frictionally engaging the article 7 in the auditory canal 14, is caused to enter the bore 12, thus relieving the auditory canal 14 of compressed air, which might otherwise result, and which would militate against the retention of the ear protector 7, against being frictionally held within the confines of the auditory canal 14.

It can readily be seen, and it is quite evident, and obvious that the insertion and removal of the ear drum protector 7, can be instantaneously effected.

I believe I have herein illustrated and described the nature of my invention, and expounded, in expository form, the teachings so that those familiar with the art will be able to practice my invention. Inasmuch as the same is susceptible of many modifications, alterations, and improvements, I hereby reserve the right to any improvements, alterations and modifications coming within the scope and spirit of my invention and disclosure, also the right to any improvements implausibly embraced in the accompanying illustrations depicting the generally suggested elemental structure of my invention, and also any modifications, improvements, or alterations, falling within the purview of the foregoing description; my invention to be limited only by the subjoined claims.

Having thus disclosed and revealed my invention, what I claim as new and desire to secure by Letters Patent is:

1. An ear protector, made of resilient material and adapted to fit frictionally within the confines of the auditory canal of a human ear, comprising a frusto-conical body portion, a manipulating knob portion near the larger end of the said frusto-conical body portion and extending beyond the confines of the auditory canal, and a reduced neck portion intermediate the said body portion and the said manipulating portion, and a multiplicity of ridges formed circumferentially about the said frusto-conical body portion defining open circumferential portions therebetween, each of said ridges being adapted to con-

tact the auditory canal of the ear in curvilinear and frictional relationship.

2. An ear protector, made of resilient material and adapted to fit frictionally within the confines of the auditory canal of a human ear, comprising a frusto-conical body portion, a manipulating knob portion near the larger end of the said frusto-conical body portion and extending beyond the confines of the auditory canal, a reduced neck portion intermediate the said body portion and the said manipulating portion, and a multiplicity of ridges formed circumferentially about the said frusto-conical body portion defining open circumferential portions therebetween, each of the said ridges being adapted to contact the auditory canal of the ear in curvilinear and frictional relationship, and bore means axially located longitudinally extending substantially through the greater portion of the said frusto-conical body portion defining a solid sound responsive portion augmenting hearing through the agency of sympathetic vibration.

3. An ear protector, made of resilient material and adapted to fit frictionally within the confines of the auditory canal of a human ear, comprising a frusto-conical body portion, a manipulating knob portion near the larger end of the said frusto-conical body portion and extending beyond the confines of the auditory canal, a reduced neck portion intermediate the said body portion and the said manipulating portion, and a multiplicity of ridges formed circumferentially about the said frusto-conical body portion defining open circumferential portions therebetween, each of the said ridges being adapted to contact the auditory canal of the ear in curvilinear and frictional relationship, the said ear protector being susceptible of preventing impairment of the ear drum by injurious sounds but maintaining the ear drum responsive to audible conversational tones.

4. An ear protector, made of resilient material and adapted to fit frictionally within the confines of the auditory canal of a human ear, comprising a frusto-conical body portion, a manipulating knob portion near the larger end of the said frusto-conical body portion and extending beyond the confines of the auditory canal, a reduced neck portion intermediate the said body portion and the said manipulating portion, and a multiplicity of ridges formed circumferentially about the said frusto-conical body portion defining open circumferential portions therebetween, each of the said ridges being adapted to contact the auditory canal of the ear in curvilinear and frictional relationship, and bore means axially located longitudinally extending substantially through the greater portion of the said frusto-conical body portion defining a solid sound responsive portion augmenting hearing through the agency of sympathetic vibration, the said ear protector being susceptible of preventing impairment of the ear drum by injurious sounds but maintaining the ear drum responsive to audible conversational tones.
